AUTOMATIC LEVELING LADDER

Claude E. Bowers, Los Angeles, Calif.

Application December 28, 1934, Serial No. 759,496

9 Claims. (Cl. 228—29)

My invention relates to ladders, more particularly to a ladder in which the legs will automatically shift to conform to uneven surfaces upon which the ladder may be positioned while the main portion of the ladder remains substantially level, and the objects of my invention are:

5 First, to provide a ladder which is strong and durable and in which the legs of the ladder will automatically shift to accommodate the ladder 10 to uneven surfaces on which it may be positioned;

Second, to provide a ladder of this class in which the weight of a person stepping on the ladder will automatically shift the legs of the 15 ladder;

Third, to provide a ladder of this class with stop means to prevent the relative shifting of the legs too far so that the ladder will tip;

Fourth, to provide a step ladder of this class 20 with means for rigidly securing the legs in various adjustable positions;

Fifth, to provide a means for providing frictional relation between the shiftable legs and their supports so that the legs tend to shift only 25 when sufficient weight is brought to bear on the steps of the ladder;

Sixth, to provide a ladder of this class in which the parts are so related in their cooperative relation that great strength and durability 30 is provided, and

Seventh, to provide a step ladder of this class which is very simple and economical of construction, automatic in its action, durable and efficient.

35 With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

40 Figure 1 is a rear elevational view of the ladder in step-ladder form shown with the legs substantially positioned on a level surface; Fig. 2 is a similar view showing one of the rear legs elevated and the adjusted relation of the other parts of the platform and steps are substantially level; Fig. 3 is a side elevational view of the ladder on a reduced scale; Fig. 4 is an enlarged fragmentary sectional view through 4—4 of Fig. 1; Fig. 5 is a further enlarged sectional view showing the clamp and its relation on an

enlarged scale; Fig. 6 is a fragmentary enlarged view of the equalizing bar and its relation with the equalizing strut, and Fig. 7 is a sectional view thereof through 7—7 of Fig. 6.

Similar characters of reference refer to similar parts and portions throughout the several views of the drawings.

The front legs 1, back legs 3, equalizing bar 4, equalizing strut 5, back leg supporting members 6 and 7, combined reinforcing and support members 8, platform 9, clamps 10, and brace members 11 and 12, constitute the principal parts and portions of my ladder as disclosed in step-ladder form.

The front legs 1 are of conventional form and positioned in spaced relation. Mounted between these front legs 1 are step members 1a supported by tie rods 1b, all in the conventional manner. Secured to the upper ends of the legs 1 in rigid relation is a platform 9, also of the conventional type and secured in conventional manner by means of brackets 9a, one on each side. Pivotally supported on these brackets 9a are the back leg supporting members 6 and 7 which are hollow, preferably oblong in cross-section, as shown, and they are reinforced at their upper ends by combined reinforcing and stop members 8, shown best in Fig. 4 of the drawings, which which form a reinforcing for the upper ends of the hollow supports 6 and 7 and also form a stop to prevent extreme shifting of the leg members 2 and 3 upwardly in their respective supports 6 and 7. The leg members 2 and 3 are telescopically mounted in the members 6 and 7 and their outer surface adapted to conform to the inner surface of the members 6 and 7 for the telescopic shifting of the members 2 and 3 in the members 6 and 7. Mounted around the lower ends of the members 6 and 7 are clamp bands 10 which are provided in one side, preferably the back side as shown, with wing screws 10a which engage a spring member 10b, shown best in Fig. 5 of the drawings, thus providing means for slightly distorting portions of the lower end of the members 6 and 7 and pressing them against the upper ends of the members 2 and 3 to provide friction between the members 2 and 3 and the members 6 and 7, and when sufficient pressure is brought thereon to lock the members 2 and 3 relative to the members 6 and 7.

45 Pivotedly connected toward the lower end of the members 2 and 3 is an equalizing bar 4. This equalizing bar 4 is preferably positioned on the front side of the leg members 2 and 3, as shown, 50

and it is provided on its back side with a member 4a which is provided with a circular recess 4b in its upper side which is adapted to receive the lower rounded end 5a of the strut member 5 so 5 that this end 5a rests on the upper surface of the groove 4b substantially in alignment with the leg members 2 and 3. The upper end of this strut member 5 is hinged to the platform 9 by means of a hinge 5b so that the strut member 5 is 10 substantially in alignment with the supports 5 and 7.

The brace members 11 and 12 are of the conventional interlocking type. The one ends of the members 12 are secured to the leg members 1 15 and the members 11 are secured to the strut 5. It will be noted that the members 11 and 12 are of the conventional type of step-ladder brace and tend to spread the leg members 1 from the members 2 and 3 and hold them in spread relation 20 by means of the strut member 5.

The operation of the ladder is as follows: The ladder is positioned on the ground with the back legs positioned on uneven surface. Then with a person stepping on the steps 1a the legs 2 and 3 25 will be raised and lowered relatively to each other conforming to the surface upon which they are positioned and the equalizing member 4 will shift, as shown in Fig. 2 of the drawings, while the platform 9 and steps 1a remain in substantially 30 horizontal or level position, the leg members 2 and 3 telescoping in the members 6 and 7. However, if an extreme shift is made the upper ends of the members 2 and 3 will engage the stop members 8 and prevent further shifting. These 35 members may be locked by the clamp screw 16a or the friction between the members 2 and 6 and the members 3 and 7 increased or decreased by this clamp screw 16a.

Though I have shown and described a particular 40 construction, combination and arrangement of parts and portions, I do not wish to be limited to this particular construction, combination and arrangement, but desire to include in the scope of my invention the construction, combination and 45 arrangement substantially as set forth in the appended claims.

Having thus described my invention, what I 50 claim as new and desire to secure by Letters Patent is:

5. In a ladder, a platform, a pair of leg members pivotally mounted on said platform, each of said leg members composed of two telescopically mounted portions with the one portion of each shiftable within the other portion, a single strut member pivotally connected with said platform intermediate said legs arranged to swing parallel with said legs, a bar pivotally connected at each of its ends with said legs and supporting the free end of said strut member in pivotal relation 60 therewith.

2. In a ladder, a platform, a pair of leg members pivotally mounted on said platform, each of said leg members composed of two telescopically mounted portions with the one portion of each 65 shiftable within the other portion, adjustable means for providing frictional relation between said members, a single strut member pivotally connected with said platform intermediate said legs arranged to swing parallel with said legs, a 70 bar pivotally connected at each of its ends with said legs and supporting the free end of said strut member in pivotal relation therewith.

3. In a ladder of the class described, leg members each consisting of a box like pivotally mounted telescopi-

cally mounted therein, a bar pivotally connected at its opposite ends to two of said telescopically mounted members near their lower ends, and a single strut member pivotally connected with said bar intermediate its ends and extending upward- 5 ly intermediate said leg members.

4. In a ladder of the class described, leg members each consisting of a box like pivotally mounted telescopic member, another member telescopically mounted therein, a bar pivotally connected at its opposite ends to two of said telescopically mounted members near their lower ends, a single strut member pivotally connected with said bar intermediate its ends and extending upwardly intermediate said leg members, and 10 a step member pivotally connected with the upper ends of each of said leg members and said strut member. 15

5. In a ladder of the class described, a pair of front legs, a platform rigidly connected to the 20 upper ends of said front legs, back legs pivotally connected with said platform, each of said back legs consisting of two telescopically mounted members, a single strut member pivotally mounted on said platform intermediate said back leg 25 members, a bar pivotally connected at its ends to the lower members of said back leg members and pivotally engageable with said strut member at its lower end.

6. In a ladder of the class described, a pair of 30 front legs, a platform rigidly connected to the upper ends of said front legs, back legs pivotally connected with said platform, each of said back legs consisting of two telescopically mounted members, a single strut member pivotally mounted on said platform intermediate said back leg 35 members, a bar pivotally connected at its ends to the lower members of said back leg members and pivotally engageable with said strut member at its lower end, and adjustable brace means 40 connecting said strut member with the front leg members intermediate the ends of said leg members and said strut member.

7. In a ladder of the class described, a pair of front legs, a platform rigidly connected to the 45 upper ends of said front legs, back legs pivotally connected with said platform, each of said back legs consisting of two telescopically mounted members, a single strut member pivotally mounted on said platform intermediate said back leg 50 members, a bar pivotally connected at its ends to the lower members of said back leg members and pivotally engageable with said strut member at its lower end, adjustable brace means connecting said strut member with the front leg 55 members intermediate the ends of said leg members and said strut member, stop means in connection with said telescopic members for limiting the relative movement of said telescopic members and each leg member.

8. In a ladder of the class described, a pair of front legs, a platform rigidly connected to the upper ends of said front legs, back legs pivotally connected with said platform, each of said back legs consisting of two telescopically mounted 65 members, a single strut member pivotally mounted on said platform intermediate said back leg members, a bar pivotally connected at its ends to the lower members of said back leg members and pivotally engageable with said strut member 70 at its lower end and also provided with a recess to receive said lower end, adjustable brace means connecting said strut member with the front leg members intermediate the ends of said leg members and said strut member, and means for pro- 75

viding friction between the telescopic members of each leg member.

9. In a ladder of the class described, a pair of front legs, a platform rigidly connected to the upper ends of said front legs, back legs pivotally connected with said platform, each of said back legs consisting of two telescopically mounted members, a single strut member pivotally mounted on said platform intermediate said back leg members, a bar pivotally connected at its ends to the lower members of said back leg members and pivotally engageable with said strut member

at its lower end and also provided with a recess to receive said lower end, adjustable brace means connecting said strut member with the front leg members intermediate the ends of said leg members and said strut member, stop means in connection with said telescopic members for limiting the relative movement of said telescopic members and each leg member, and means for providing friction between the telescopic members of each leg member. 5 10

CLAUDE E. BOWERS.
